CATALOG COVER BINDER
Melville Embry Foster, 16 Thomas Ave. S.,
Minneapolis, Minn.
Filed Sept. 26, 1960, Ser. No. 53,300
1 Claim. (Cl. 129—23)

This invention relates to catalog covers. More particularly it relates to catalog covers of the loose leaf type which are very inexpensively manufactured of a semi-durable material and which are used by many industrial firms to retain up to date information that fluctuates rapidly.

There is a definite need in industry for a catalog cover having a suitable binding which permits the ready insertion of new sheets or substitution of sheets therein and which is manufactured of an unusually inexpensive material and yet meets the requirements of the trade in that it provides a sufficiently sturdy and rigid cover to protect the individual sheets and to preclude undue deformation of the folder during normal handling. My previous U.S. Letters Patent No. 2,891,554 constitutes a substantial improvement over such folders as heretofore known and it has been well accepted by the industry. I have found, however, that even this folder which is relatively inexpensive can be improved upon, simplified, and redesigned to provide a novel and relatively inexpensive construction which adequately meets the needs of the trade. My invention is designed to provide additional advantages and to eliminate a substantial portion of the cost of the construction of a cardboard catalog cover.

It is a general object of my invention to provide a novel and improved catalog cover which is unusually simple in construction and relatively inexpensive as compared to catalog covers heretofore known.

A more specific object is to provide a novel and improved catalog cover binder which can be manufactured very inexpensively and which performs in an improved manner.

Another object is to provide a novel and improved catalog cover and binder therefor which is extremely simple in construction and assembly and yet highly efficient in function to provide an improved catalog cover which adequately meets the need of the trade.

Another object is to provide a catalog cover binder which can be manufactured separately and can be applied to a simple cover to furnish a highly satisfactory loose leaf cover member.

Another object is to provide a novel and improved catalog cover binder so constructed and arranged to inherently provide and convert a normally inadequately rigid back member into a rigid back member which adequately meets the needs of the trade and substantially strengthens the entire cover.

Another object is to provide a novel and improved catalog cover binding post so constructed as to provide increased flexibility in purpose and function so as to furnish more desirable holding means for individual sheets to be carried within the catalog cover.

These and other objects and advantages of this invention will more fully appear from the following description, made in connection with the accompanying drawings, wherein like reference characters refer to the same or similar parts throughout the several views, and in which:

FIG. 1 is a perspective view of one embodiment of my invention.

FIG. 2 is a vertical sectional view of the binder taken along line 2—2 of FIG. 1, and

FIG. 3 is an exploded view of the binder also taken along line 2—2 of FIG. 1.

FIGS. 1-3 show a catalog cover indicated generally by the numeral 5 embodying my invention. As shown, the

2

catalog cover 5 includes a sheet 6 of semi-rigid material such as thin cardboard which is folded over along spaced parallel lines indicated at the points 7 and 8 into a front cover element 9, a back cover element 10 and an intermediate back area 11 extending longitudinally of the cover. The front cover 9 has an inner surface 9a and an outer surface 9b and the back cover 10 has an inner surface 10a and an outer surface 10b as best shown in FIG. 2.

The semi-rigid sheet of cardboard 6 when so folded is 10 unsatisfactory for use as a catalog cover in that the material from which the sheet 6 is made is of insufficient rigidity to satisfactorily protect sheets which would be placed therewithin. In addition, of course, it is unsatisfactory 15 because no means for retaining such sheets has been provided. It is important to note however, that because of its texture and lack of rigidity this sheet may be made of a relatively inexpensive material which when combined with my loose leaf page binder provides a very inexpensive but highly satisfactory catalog cover.

20 My loose leaf page binder which is indicated generally by the numeral 12 is also formed of semi-rigid material such as cardboard which is thin and shown in an elongated strip. This strip 13 is scored along a line extending longitudinally of the strip at the point 14 to divide the 25 strip into a relatively narrow marginal minor portion 15 and a relatively wide major portion 16. The minor portion 15 thereupon becomes in the nature of a flap while the major portion 16 constitutes a base therefor.

20 A plurality of embossments 17 are formed in the strip 30 13 and are spaced longitudinally thereof. For the sake of simplicity a single embossment is described and it will be understood that each of the embossments are identical in structure and therefore corresponding numerals have been applied thereto in the drawings. As best shown in 35 the FIG. 1 the embossments are generally circular in configuration and form circular recesses 18 in the major portion 16 of the strip. These recesses 18 are formed in the under surface of the major portion 16 and each is provided with a centrally disposed opening 19 which is 40 formed through the strip.

Disposed within each of the recesses 18 and extending upwardly through the associated openings 19 is a flexible tubular member which has been indicated generally by the numeral 20. These tubular members 20 are preferably formed of rubber or some similar flexible resilient material. Each of the tubular members 20 is provided with a flat, thin, highly flexible base 21 and an upstanding tubular portion 22, the upper end of which is open. It will be noted that the flat thin base is generally circular 50 in configuration and is less than one half in thickness as compared to the thickness of the wall structure of the tubular member 20. It will also be noted that when the tubular member 20 is applied to the strip 13 so that the tubular portion 22 extends upwardly through the opening 55 19, the flat base 21 is substantially entirely received within the recess 18 of the embossments.

There is also provided a plurality of headed members indicated generally by the numeral 23 one each of which is received and positively gripped by the resilient tubular 60 portion 22 of one of the tubular members 20. It will be noted that the headed members 23 is each provided with a head 24 from which a post member 25 extends downwardly. The post member 25 has its outer surface serrated as shown in FIG. 3.

65 After the tubular members have been inserted through the strip 13 the under surface of the strip 13 is applied to the sheet 5 and adhered to it with a layer of adhesive 26. It will be noted that the major portion 16 of the strip 13 is applied to the inner surface 10a of the back cover element immediately adjacent the back area 11 and that the relatively minor portion 15 or flap is applied to the back area 11. The marginal portion 15 is of the same

width as the back area 11 and of the same length so that the two elements are coextensive.

I have found that when a binder member such as described herein is applied with adhesive to the inner surface of such a sheet 6 in the manner hereinbefore described, the flap 15 cooperates with the back area 11 to provide a rigid back for the cover and imparts the necessary rigidity to the entire cover to satisfactorily meet the needs of the trade. The loose leaf sheets, of course, are applied to the tubular members 20 after the headed members 23 have been removed with the tubular portions 22 extending upwardly through the sheets. After the sheets have been applied to the tubular members 22 the headed members 23 are replaced as shown in FIGS. 2 and 3 to securely hold these sheets in place.

One of the advantages of my invention is that the thin flexible base member 21 imparts sufficient flexibility to the upstanding tubular members 20 such that the sheets which are secured thereby are less likely to be torn when subjected to a slight pulling action by the user. In such instances the highly flexible base 21 permits the tubular portion 22 to bend with the strain. Such flexibility precludes tearing of the sheets in many instances where a completely rigid member would cause the sheets to be torn. Even the post members in my previous Patent No. 2,891,554 is not as satisfactory in this respect because the base member there is relatively rigid and is of such thickness as to preclude any appreciable use. As a result pulling on a sheet which is held by such a member will cause the sheet to tear quite readily.

Another advantage of my invention, in addition to the fact that the back 11 is made rigid by the flap 15, is the fact that the entire catalog cover when constructed in accordance with my invention is substantially cheaper than any heretofore known and yet functions in a highly satisfactory manner and meets the needs of the trade. In addition such a catalog cover is much easier to assemble and eliminates much of the inconvenience involved in replacing or substituting individual sheets from within a large number or volume already within the book or holder.

The material from which the sheets 6 and the strip 13 are made is of a weight commonly referred to as "tag stock."

The sheet 6 and the elongated strip 13 are each formed of a sulphate fiber material commonly referred to as manila tag stock which has a weight of 175 pounds per ream consisting of 500 sheets with dimensions each of 24 inches by 36 inches. Such sheets having a thickness of 0.0125 each.

It will, of course, be understood that various changes may be made in the form, details, arrangement and pro-

portions of the parts without departing from the scope of this invention which consists of the matter shown and described herein and set forth in the appended claim.

What is claimed is:

5 A catalog cover comprising a sheet made of thin cardboard folded along spaced adjacent parallel lines into a front cover element, a back cover element, and a back area disposed intermediate said elements and extending generally normal thereto, said elements having an inner and an outer surface, and a binder comprising an elongated strip of thin semi-rigid cardboard material having an upper surface and an under surface, said strip being scored longitudinally and thereby divided into only a relatively narrow marginal minor portion and a relatively wide major portion, said major portion having a plurality of longitudinally spaced preformed permanent embossments formed therein and an opening formed through said strip and disposed centrally within each of said embossments, said embossments providing recessed areas in the under surface of said strip, a plurality of flexible tubular members each having a flat thin flexible base, each of said tubular members having its flat flexible base fitted snugly within one of said recessed areas of said strip and having its tubular portion extending upwardly through the associated said opening of said strip to lock each tubular member in position, a plurality of headed members each having a serrated post element which extends outwardly from its head and is received in positively gripped relation within the tubular portion of one of the tubular members, and adhesive means between substantially the entire under surface of said strip and the inner surface of said sheet and fixedly securing the same thereto, said adhesive means securing said minor marginal portion of said strip directly to and along the back area of said sheet and cooperatively forming therewith a rigid back for the cover and securing the major portion of said strip along the inner surface of the back cover element adjacent said back area with said tubular members upstanding and cooperatively forming a loose leaf catalog from which pages may be easily, quickly and readily removed or substituted.
